UNITED STATES PATENT OFFICE.

JAMES B. McMAHON, OF BOSTON, MASSACHUSETTS.

DESIGN FOR A MUFF.

SPECIFICATION forming part of Design No. 25,189, dated February 18, 1896.

Application filed October 23, 1895. Serial No. 566,656. Term of patent 34 years.

To all whom it may concern:

Be it known that I, JAMES B. McMAHON, a citizen of the United States, residing at Boston, in the county of Suffolk and State of Massachusetts, have invented and produced a new and original Design for Muffs, of which the following is a specification.

Reference is to be had to the accompanying drawings, in which—

- 10 Figure 1 is a perspective view of a muff embodying my design, and Fig. 2 is an end view thereof.

In the said drawings, the numeral 2 represents a muff, the ends 3 of which are provided 15 with an ornamentation consisting of lines or ridges 4, which may be formed or constructed in any suitable manner. These lines 4 extend in a general radial direction, and each

of them forms a double curve, which curves are alternately disposed—that is to say, each pair of them alternately recede from and approach each other, as illustrated. In addition to these lines or ridges on the end of the muff, my design also includes similar straight ridges formed on the longitudinal exterior 25 thereof and parallel therewith, as shown at 5.

I claim—

The design for a muff substantially as shown and described.

In testimony whereof I have hereunto subscribed my name this 19th day of October, A. D. 1895.

JAMES B. McMAHON.
